ATTORNEY

UNITED STATES PATENT OFFICE.

JAMES M. TAPPEN, OF NEW YORK, N. Y., ASSIGNOR TO DUNHAM, BUCKLEY & CO., OF SAME PLACE.

DESIGN FOR TRIMMING.

SPECIFICATION forming part of Design No. 19,300, dated September 3, 1889.

Application filed February 13, 1889. Serial No. 299,742. Term of patent 3½ years.

To all whom it may concern:

Be it known that I, JAMES M. TAPPEN, a citizen of the United States, residing in the city, county, and State of New York, have 5 invented and produced a new and original Design for Trimmings, of which the following is a specification.

The design is shown in the accompanying drawing, which forms a part of this specification, and which represents a face view of a piece of braid or trimming having my new design.

The longitudinal central portion of the trimming presents a series of parallel cross-paralellogrammic figures *a*, each of which presents a series of parallel twisted-cord-like figures *b*, crosswise of the trimming. Alternating be-

tween these figures *a* are a series of plain or block-like parallelogrammic figures *d*, representing an interwoven band-like filling within 20 the trimming. The borders of the trimming present a surface ornamentation of a longitudinal serpentine-like figure *e*. These borders are in the form of longitudinal bands on each side of the longitudinal central portion 25 of the trimming.

I claim—

The within-described design for a braid or trimming, substantially as represented in the accompanying drawing.

JAMES M. TAPPEN.

Witnesses:

EDGAR TATE,
EDW. M. CLARK.
